[57] CLAIM

The ornamental design for a control panel for an air conditioning system, substantially as shown and described.

DESCRIPTION

FIG. 1 is a front elevational view of a control panel for an air conditioning system showing our new design, the rear, not shown, is substantially flat plain and unornamented;

FIG. 2 is a right side elevational view thereof, the left side being a mirror image thereof;

FIG. 3 is a bottom plan view thereof, the top plan being a mirror image thereof.

FIG. 2

FIG. 1

FIG. 3
